DESIGN FOR A DRESS

Mary Gorelick Schor, New York, N. Y.

Application June 1, 1939, Serial No. 85,277

Term of patent 3½ years

To all whom it may concern:

Be it known that I, Mary Gorelick Schor, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design,

Fig. 2 is the rear view of Fig. 1.

The instant dress comprises a knitted blouse portion and a woven skirt detachably connected at the waistline, the contrasting collar and tab members of the blouse matching the skirt in fabric and color as shown.

I claim:

The ornamental design for a dress, substantially as shown and described.

MARY GORELICK SCHOR.
